UNITED STATES PATENT OFFICE.

REGINALD H. EARLE, OF ST. JOHNS, NEWFOUNDLAND.

IMPROVEMENT IN ICE-CREEPERS.

Specification forming part of Letters Patent No. **145,310**, dated December 9, 1873; application filed October 4, 1873.

To all whom it may concern:

Be it known that I, REGINALD H. EARLE, of St. Johns, in the Province of Newfoundland, have invented a new and useful Improvement in Ice-Creeper, of which the following is a specification:

Figure 1 is a top view of my improved ice-creeper. Fig. 2 is a longitudinal section of the same taken through the line *x x*, Fig. 1. Fig. 3 is a cross-section of the same taken through the line *y y*, Fig. 1. Fig. 4 represents a wrench for operating the set-screw.

Similar letters of reference indicate corresponding parts.

My invention has for its object to furnish an improved ice-creeper, neat and simple in construction, and convenient in use, and which will enable the wearer to conveniently and safely walk over the smoothest ice. The invention consists in the combination of the grooved plate, the sliding halved plates provided with inwardly-projecting spikes at their turned-up outer ends, the set-screw, and the downwardly-projecting spikes with each other, as hereinafter fully described.

A is a narrow plate of such a length as to reach across the sole of the boot. Upon the upper side of the plate A, along its side edges, are formed grooves to receive the side edges of two plates, B, the inner parts of which are halved, so as to overlap each other without producing any extra thickness. The movements of the plates B, as they are slipped out

and in, are limited by pins attached to the upper side of the ends of the plate A, and which project through short longitudinal slots in the plates B. The outer ends of the plates B are bent upward at right angles, and have spikes C attached to them to enter the edges of the boot-soles. D is a set-screw, which passes up through a screw-hole in the middle part of the plate A, so that its forward end may press against the plates B and press them against the flanges that form the grooves in which the edges of the said plates B work. To the under side of the plate A are attached two or more short spikes, E, to take hold of the ice, and thus prevent the wearer from slipping.

In using the creepers, the set-screw D is loosened, and the plates B are drawn outward. The creeper is then placed upon the sole of the boot, and the plates B are forced inward, forcing the spikes C into the edges of the boot-sole. The set-screw D is then tightened, and the creepers are ready for use.

Having thus described my invention, I claim as new and desire to secure by Letters Patent—

The ice-creeper, constructed of the grooved plate A, the plates B, sliding on each other, and having spikes C, and the set-screw D, arranged as shown and described.

REGINALD HEBER EARLE.
